(57) **CLAIM**

The ornamental design for a lighting accessory for a portable electronic device, as shown and described.

DESCRIPTION

FIG. 1 is a front perspective view of a lighting accessory for a portable electronic device showing our new design; FIG. 2 is a rear perspective view thereof; FIG. 3 is a front view thereof; FIG. 4 is a rear view thereof; FIG. 5 is a top view thereof; FIG. 6 is a bottom view thereof; and, FIG. 7 is a left side view thereof.

The broken lines illustrate portions of the lighting accessory for a portable electronic device and form no part of the claimed design.
